DRAFT GEAR

John L. Eler, Cleveland, Ohio, assignor to National Malleable and Steel Castings Company, Cleveland, Ohio, a corporation of Ohio

Application October 20, 1943, Serial No. 506,934

6 Claims. (Cl. 213—36)

This invention relates to railway draft gear and more particularly pertains to improvements in the device shown and described in an application, Serial No. 408,488, filed August 27, 1941, of Archwood J. Kashubeck, Hubert L. Spence and John L. Eler.

The present invention is directed to means for preventing improper assembly of the friction shoes. Another feature resides in the cooperation of the aforesaid means with other parts of the draft gear to facilitate assembly of the device.

In the drawings:

Figure 1 is a view of a draft gear embodying my invention, shown partly in elevation and partly in section taken on line 1—1 of Fig. 3, the parts being in normal position.

Figure 2 is a view similar to Fig. 1 with the parts in fully compressed position.

Figure 3 is an elevational view at right angles to Fig. 1 with part of one of the housings broken away.

Figure 4 is a transverse sectional view, taken on line 4—4 of Fig. 3.

Figure 5 is a view of the shoe operating plunger showing the method of assembly of the friction shoes; and

Figure 6 is a perspective view of one of the friction shoes.

The draft gear disclosed in the drawings generally comprises a pair of housings 10 and 11. Housing 10 has a pair of rockers 12 mounted on seats 13 on end wall 14 adapted to rotate a limited amount with respect to the housing. Each rocker comprises a transversely extending base portion 15 and a longitudinally extending arm 16 having a sloping friction surface 17. Spring seats 18 extend between the rockers on each side of arms 16 and support one end of springs 19. Surfaces 20 on the rockers are sloped away from the line of contact with spring seats 18 so that springs 19 will always tend to rotate the rockers toward the center of the draft gear.

Shoes 21 engage friction surfaces 17 on the rockers and each is formed with a cylindrical seat 22 adapted to receive a similarly shaped projection 22a on one end of a shoe actuating post or plunger 23. Projecting inwardly from the side walls of housing 10 are shelves 24 which overlie surfaces 25 on the plunger and limit outward movement of the plunger relative to the housing. Spring seat 26 rests on outer side of shelves 24 and supports one end of spring 27. Housing 11 receives the opposite ends of springs 19 and 27 and plunger 23. Springs 19 and 27 normally

tend to force housings 10 and 11 apart until such movement is limited by engagement of the heads 31 of bolts 30 with housing 11 and engagement of nuts 32 with housing 10.

The end of plunger 23 contained in housing 11 is normally spaced from end wall 33 of said housing until a predetermined amount of movement of the housings toward each other takes place. Thereafter, wall 33 engages the plunger and it moves with housing 11, sliding shoes 21 along friction surfaces 17 of the rockers, causing the latter to rotate against the resistance of springs 19.

Projecting laterally from the sides of the lower end of plunger 23 are lugs 35, surfaces 25 of which are adapted to engage the under sides of shelves 24 to limit movement of the plunger in one direction. Spaced from lugs 35 are projections 36, one on each side of the plunger, which cooperate with the shoes for the purpose now to be described. On each shoe is a pair of arms 37 extending inwardly toward the opposing shoes between lugs 35 and projections 36. At the end of each arm is an upwardly projecting lug 38, which, when the draft gear is in released position, lies between a pair of lugs 35 on the adjacent side of the plunger. Arms 37 and lugs 38 are normally spaced from lugs 35 and projections 36 sufficiently to permit operation of the draft gear. However, when assembling the shoes and plunger in housing 10 the shoes are first supported on the plunger in the manner shown at the right in Fig. 5. In this position each of lugs 38 engages a lug 35 and projections 36 are in engagement with the shoes substantially at the juncture of arm 37 with the shoes. The shoes at the left in Fig. 5 illustrate the method of assembling the shoe by rotating arms 37 and lugs 38 between lugs 35 and projections 36 until the position is reached as shown at the right of the figure. With the shoes resting on the plunger as above described, these parts may be lowered into housing 10 at one side of shelves 24 until the shoes are below the shelves after which the plunger and shoes can be moved as a unit to the center of the device. It will be observed that the shoes are free to rotate, so far as lugs 35 and 38 and related projections 36 are concerned, so as to rotate from the position shown in Fig. 1 to that shown in Fig. 2 during compression of the draft gear.

The terms and expressions which I have employed are used as terms of description and not of limitation, and I have no intention, in the use of such terms and expressions, of excluding any

equivalents of the features shown and described or portions thereof, but recognize that various modifications are possible within the scope of the invention claimed.

What I claim is:

1. A draft gear comprising a pair of followers, spring means normally forcing said followers apart, friction members adapted to rotate in one of said followers against the resistance of said spring means, friction shoes engaging said friction members, a shoe actuating member engaging said shoes, spaced lugs on said shoe actuating member, and means on said shoes engageable with said lugs for retaining said shoes on said shoe actuating member during assembly of said parts with said followers.

2. In a draft gear a pair of followers, spring means between said followers, friction members engaging said spring means, friction shoes engaging said friction members, a shoe actuating member engaging said shoes having spaced lugs thereon, and means on said shoes engageable with said lugs for retaining said shoes on said shoe actuating member during assembly of said parts.

3. In a draft gear a pair of followers, spring means between said followers, friction members engaging said spring means, friction shoes engaging said friction members, a shoe actuating member engaging said shoes, laterally projecting lugs on one end of said shoe actuating member, and means on said shoes extending between

said lugs and engageable therewith for maintaining said shoes on said shoe actuating member during assembly of said parts.

4. In a draft gear a pair of followers, spring means between said followers, friction members engaging said spring means, friction shoes engaging said friction members, a shoe actuating member engaging said shoes, laterally projecting lugs on said shoe actuating member, and an arm 10 on each of said shoes extending between said lugs for maintaining said shoes in position during assembly of said parts in the draft gear.

5. In a draft gear a pair of followers, spring means between said followers, friction members 15 engaging said spring means, friction shoes engaging said friction members, a shoe actuating member engaging said shoes, an arm on each shoe extending inwardly of said draft gear, and means on said shoe actuating member on each 20 side of said arms adapted to limit pivotal movement of said shoes with respect to said shoe actuating member.

6. In a draft gear a pair of followers, spring means between said followers, friction members 25 engaging said spring means, friction shoes engaging said friction members, a shoe actuating member engaging said shoes, a pair of arms on each shoe extending inwardly of said draft gear and a plurality of lugs adjacent said arms adapted 30 to limit pivotal movement of said shoes with respect to said shoe actuating member.

JOHN L. ELER.
